UNITED STATES PATENT OFFICE.

GEORGE J. KLEIN, OF CLEVELAND, OHIO.

DESIGN FOR A CYLINDER LANTERN.

Application filed July 12, 1924. Serial No. 10,125. Term of patent $3\frac{1}{2}$ years.

To all whom it may concern:

Be it known that I, GEORGE J. KLEIN, a citizen of the United States, residing at Cleveland, in the county of Cuyahoga and State of Ohio, have invented a new, original, and ornamental Design for a Cylinder Lantern, of which the following is a specification, reference being had to the accompanying drawing, forming a part hereof.

Figure 1 is a top plan view of a cylinder lantern showing my new design.

Fig. 2, is a bottom or inverted end view of the same.

Fig. 3 is a side elevation of the same.

I claim:—

The ornamental design for a cylinder lantern, as shown.

GEORGE J. KLEIN.
